UNITED STATES PATENT OFFICE

CARL WESSEL, OF BORBECK, NEAR ESSEN-ON-THE-RUHR, GERMANY, ASSIGNOR TO
THE FIRM: CARL STILL, OF RECKLINGHAUSEN, WESTPHALIA, GERMANY

COKE OVEN

Application filed June 16, 1926, Serial No. 116,359, and in Germany June 16, 1925.

My invention relates to externally heated coke ovens, especially coke ovens of the chamber type, in which the volatile products of distillation are withdrawn through the base of the chamber.

The main object of my invention is to obviate injurious effects of the high temperatures prevailing in the base portions of the coking chambers both on the volatile products and on the passages and apparatus leading said volatile products through the said base portions.

According to the invention an exhaust passage for the withdrawal of these gaseous products is constructed within the brick-work at the base of the chamber and is insulated from the surrounding walls by an air or gas space acting as an insulating or even cooling means or by solid insulation materials.

The passage can consequently expand and contract independently of the brick-work and any decomposition of the gases and vapours traversing the passage due to direct contact with heated walls is avoided.

In one form of construction, the passage is formed as a tube extending along the whole length of the coke oven chambers, slots at the top of the tube being provided which register with similar openings preferably arranged in the centre of the base of each oven.

In a modified construction, the whole surface of the base is utilized for the withdrawal of the volatile products of distillation and the exhaust passage for these products is formed by a box-shaped trough made of metal or ceramic materials open above and closed below. A sieve plate supported on bearing bars resting on the exhaust trough is provided with openings allowing the passage of the volatile products, but retaining the solid particles. Cooling mediums can be introduced into hollow spaces provided in the trough.

In the accompanying drawings which represent two examples of coke ovens provided with exhaust passages according to the invention—

Fig. 1 is a vertical cross section and Fig.

2 a vertical longitudinal section of a coke oven chamber, this example constituting one embodiment of my invention.

Figs. 3 and 4 respectively are a vertical cross section and a vertical longitudinal section of a coke oven with a modified arrangement for withdrawing the gases and vapours, and Fig. 5 is a plan of the sieve plate and its supports, looking downwards.

Referring to Figs. 1 and 2, the brickwork of the oven is indicated at *a*; *b* is the tubular exhaust tube preferably subdivided, as to its longitudinal direction, into several abutting portions which tube can be made of metal or ceramic materials and is separated from the brickwork by an air space *c* and supported at intervals by projections *c'* of the brickwork. This space *c* acts as a heat insulating means and can conveniently be replaced by any solid insulating material. *d* Slots in the central portion of the upper part of the tube *b* register with openings *e* in the centre of the base *f* of the oven chambers.

The openings *e* in the base *f* of the chamber can be covered with sieve plates or the like in order to lessen any discharge of small particles of coal or coal dust. Any coal or coke particles which pass through the openings allotted to the passage *b* can be easily removed from time to time, for example by blowing through a jet of steam.

In order to prevent any volatile condensates from the distillation products finding their way into the openings *e* and the passage *b*, and forming with the particles of coal which have entered the passage an incrustation which might choke the passage, the base *f* is preferably raised in the centre and slopes downwards on each side as shown in Fig. 1. The condensates which eventually arise then flow laterally to the hot walls of the oven and are evaporated on the base of the oven and cool the latter to the required extent. The described invention can not only be

used with new ovens but can also be applied to existing ovens, which are to be converted to withdraw the gaseous products of distillation through the base of the chamber. In this case, a special and separate body of new

brickwork can be erected on the existing former base of the chamber, which brick-work surrounds the tube *b*, so that a new base *f* is formed at a slight distance above the old base. The slight drawback due to the reduction in the effective height of the chamber is fully compensated by the advantages gained with the new apparatus and method of working.

10 In case the arrangement of openings *e* in the centre alone of the base *f* should be insufficient for the special conditions of the coke oven used, several of such openings can be provided instead of the one shown in 15 Fig. 1.

The arrangement according to the invention has the important advantage that the gases are withdrawn through the base of the chamber in the quickest and shortest 20 path into a space, namely the tube *b*, which is well protected against any injurious heating by the brickwork. The advantages which are connected with the withdrawal of the gases downwards through the base of 25 the chamber and which consist in fully protecting these distillation products against decomposition by heat have really been ensured for the first time by the apparatus of this invention. At the same time this heat 30 insulation of the tube *b* imparts an increased durability and allows the apparatus to be made of material which need not be refractory. The form and method of construction of the device are very simple and therefore 35 very cheap.

In the modified construction shown in Figs. 3, 4 and 5, one feature is that the whole surface of the base is utilized to withdraw the volatile products of distillation.

40 In Fig. 3 the cross section of the coal charge lying inside the coking chamber and undergoing carbonization has been shown too. In this representation there has been supposed that use has been made of a kind 45 of coking coal and of operation in which during the carbonization process two layers *r* of partially coked coal running parallel to the two side heating walls are formed and advance gradually to the centre which are 50 nearly gas tight. On the inside between these two layers *r* lies raw unconverted coal *q* of a loose structure and a moderate temperature; on the two outsides exists finished coke *p* of a very dense structure and 55 of a high temperature.

In the modified embodiment being in consideration the exhaust passage consists essentially in a box-like lower portion *i* open above and sieve plates *h* lying loosely thereon. The box *i* which is independent of the brickwork can be made of metal, for example cast iron, or any other suitable material of ceramic nature, and consists, in the example shown, of two hollow members *u* which 60 abut in the centre of their length and are

connected by a strip *k* continuous over the whole length of the chamber. In the longitudinal direction, the box *i* is subdivided into several short abutting pieces which are held together by longitudinal bolts *l*. The 70 open upper surface of the box *i* is bridged by a number of cross bearers *m* placed at suitable intervals. An upright rim extending over the whole length of the chamber is formed by projections *n* arranged between 75 the cross bearers *m* and extending on top of the longitudinal sides of the box *i*, the upper surfaces of said rim being flush with the upper surfaces of the bearers *m*. These bearers *m* and projections *n* are covered with the several loosely attached sieve plates *h* which are arranged adjacent to one another and form a continuous base provided with numerous openings for the withdrawal of 80 the gases.

The hollow spaces *o* in the box *i* which may extend over the whole or only part of the length of the chamber, serve to conduct *a*, preferably gaseous, cooling agent such as steam or air or waste furnace gases. This cooling medium effects an immediate cooling of the distillation products flowing into and through the passage *i* from the relatively dense layers of hot coke *p* at a high temperature near the walls of the oven. At the same time the hollow spaces *o* traversed or filled by gaseous medium insulate the exhaust gases from the action of the highly heated brickwork which lies laterally and below the passage. The hollow spaces *o* can obviously be replaced or supplemented by other forms of heat insulating devices.

The distillation products are withdrawn from the whole surface of the base, so that the gases and vapours can stream both from the central part of the chamber containing loose un-reduced coal *q* at a low temperature and from the hot coke *p* which is separated from *q* as has been explained above by nearly gas-tight layers *r* of partially formed coke 105 impregnated with particles of thick tar.

The gaseous medium flowing in the spaces *o* both cools and insulates the volatile products in the passage *i* and protects more especially the cool gases and vapours streaming from the cool unconverted coal *q*, which contain the valuable tar constituents, against any objectionable overheating due to mixing in the passage with the hot gases from the outer hot coke layers *p*. If steam is used as the cooling medium in *o*, the steam which becomes superheated can be led entirely or partially into the coke oven chamber above the charge of coal. This steam is then preferably withdrawn through the spaces *s* formed between the walls of the chamber and the outer surface of the coke *p* by the shrinkage of the coke and through the fissures which are always formed in the coke and thereby considerably increases the yield 115 120 125 130

- of ammonia which is locally confined at these places; the high temperature of the superheated steam prevents any undesired cooling of the coked charge.
- 5 At the inner surfaces of the two coking layers r many volatile products are formed, such as steam and tarry constituents. The gases and vapours set free at these parts naturally tend to pass into the spongy raw
- 10 coal q offering little resistance; they form a relatively cold and, therefore, specifically heavier mixture of gas and vapour which by its weight tends to flow downwards. In the coked portion p lying outside the coking
- 15 layers r , mainly permanent gases are liberated, more particularly hydrogen and ammonia. These latter gases are very hot, thereby specifically light, and tend consequently to flow upwards.
- 20 If, in case of using a coal and a coking operation as supposed, all the products are drawn off at the centre of the base, only the gases and vapours developed in the inner space q containing unconverted coal can
- 25 freely flow downwards, owing to the practically complete closure made by the nearly dense layers r . On the other hand, the gases developed in the coke portions p , and among them the ammonia, must take an irregular path, in the first place by rising at the hot side walls and passing to the free upper surface of the charge below the ceiling of the oven and thence through the loose coal q ; in this case decomposition and a
- 30 reduced output both of the valuable ammonia and also of the hydrocarbon vapours developed in q unavoidably occur when these volatile products meet the hot gases from the highly heated coke p . The same
- 35 difficulties naturally occur in such cases if the exhaust is only at the outside portions of the base of the chamber, i. e., near the side walls, since the cool gases and vapours of the unconverted coal q are then driven to the outer
- 40 space containing the hot coke p . If, however, the whole surface of the base is utilized for withdrawing the products of distillation, the difficulties above mentioned are entirely obviated. In this way an easy down-
- 45 ward flow is provided both for the gases formed in q and also for those formed in p . In order to ensure this condition, it is only necessary to maintain in the passage i a pressure less than the amount of each of the
- 50 different pressures present at the base of the chamber in the inner space q and the outer space p .
- The holes or slots in the sieve plates h are not, as might have been expected, choked up to any important extent. This is, apparently, due to the observed fact that in general no liquid or viscous condensates (tar or the like) reach the sieve plates and, therefore, do not ooze through these holes into the passage f . By the division of the apparatus
- 55 into a lower box and separate sieve plates, loosely laid thereon, the unavoidable expansion due to heat is efficiently allowed for. The loosely laid cross bearers m permit the use of sieve plates of relatively weak and light construction which can be easily replaced when worn at small cost and during the working operation.
- 60 What I claim is:—
1. In a coke oven, means forming a coking chamber, means for leading off gaseous distillation products from the coking chamber comprising a conduit arranged within the first named means but independent thereof and below the coking chamber, means forming a container for insulating media arranged to protect the products in the conduit from the heat of the oven, and means establishing a communication between said coking chamber and conduit.
- 65 2. In a coke oven, means forming a coking chamber, means for withdrawing gaseous distillation products from the coking chamber comprising a conduit arranged within the first named means but independent thereof and arranged below the coking chamber, an open-work supporting member supported above said conduit and adapted to provide communication between the coking chamber and said conduit over the whole base area of the coking chamber, and insulation protecting said conduit from the heat of the oven.
- 70 3. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means for protecting the products of distillation in the conduit from the heat of the oven.
- 75 4. In a coke oven, means for leading off gaseous distillation products from the coking chamber thereof comprising a box-like body supported upon the existing base of the coking chamber and carrying bearer bars, sieve plates supported on said bearer bars and forming a surbase and providing means for connecting the box-like body with the coking chamber, and means for protecting the products of distillation in said box-like body from the heat of the oven.
- 80 5. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means forming a container for insulating media arranged to protect the products in the conduit from the heat of the oven.
- 85 6. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 90 7. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 95 8. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 100 9. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 105 10. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 110 11. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 115 12. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 120 13. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 125 14. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.
- 130 15. In a coke oven, means for leading off gaseous distillation products from the coking chamber thereof comprising a conduit arranged within but independent of the oven and supported upon the existing base of the coking chamber, a surbase provided with a plurality of openings for connecting the conduit with the oven chamber, and means establishing a communication between said coking chamber and conduit.

6. In a coke oven, means for leading off gaseous distillation products from the coking chamber thereof comprising a box-like body supported upon the existing base of the oven chamber and carrying bearer bars, sieve plates supported upon said bearer bars and forming a subbase and providing means for connecting the box-like body with the oven chamber, and means forming a container for insulating media arranged to protect the products in said box-like body from the heat of the oven.

10 In testimony whereof I affix my signature.
CARL WESSEL.
